NON-LINEAR FUNCTIONAL OPERATOR
 Richard Peretz, Watermael-Boitsfort, Belgium, assignor to
 Ateliers de Constructions Electriques de Charleroi
 (ACEC), Brussels, Belgium, a joint-stock company of
 Belgium

Filed July 14, 1961, Ser. No. 124,187
 2 Claims. (Cl. 307—88.5)

This invention relates to a new type of a circuit, called non-linear functional operator, delivering an output signal which is a dependent variable of the input voltage according to a non-linear function. Such operators can be used in automatic regulation systems and in electronic analog computers.

A known principle of operation of such circuits consists of producing an output signal which varies as the input voltage according to a function which can be represented by a broken line constituting an approximation of the desired function. This principle has been disclosed in the book "Electronic Analog Computers" by Korn, A. G. and Korn, T. M. pages 290 to 297 (McGraw-Hill, New York, 1956).

A general object of the present invention is to provide a non-linear functional operator which operates according to the above-mentioned principle, simple and accurate, easy to use, sturdy and stable.

Another object of the invention is to provide a non-linear functional operator comprising branches each constituted by Zener diodes connected in series at the junction points of which voltages appear which can be represented, as a function of the input voltage, by straight lines intersecting the horizontal axes in spaced points and comprising means for separately varying the slope of these linear voltages and for combining them so that the resulting voltage varies by approximation according to any desired non-linear function.

Further objects and advantages will readily become apparent upon reading the following specification taken in conjunction with the drawings in which:

FIG. 1 represents an element of a non-linear functional operator according to the invention;

FIG. 2 is a diagram showing the variation of output voltages of this element as a function of the input voltage;

FIG. 3 shows a circuit allowing the slope of these output voltages to be varied;

FIG. 4 is a schematic of a particular form of a non-linear functional operator in which two elements as shown in FIG. 1 are used;

FIG. 5 is a schematic of another particular form of realization;

FIG. 6 shows a circuit for smoothing the angles of the variation of an output voltage represented by a broken line;

FIG. 7 shows a still further form of realization of an operator.

Referring to FIG. 1, Zener diodes $Z_1, Z_2, Z_3 \dots Z_n$ are connected in series with a silicon diode D_1 . An input voltage V_1 being applied to terminals V_1 with a polarity corresponding to the conduction direction of diode D_1 and assuming that the input voltage increases, there will appear at terminals V_1 a voltage V_1 once the Zener voltage of Z_1 has been reached. This voltage V_1 will vary according to FIG. 2, increasing from zero until when V_1 has reached the Zener voltage of the second diode Z_2 , a voltage V_2 appears which also increases from zero, and so forth. Thus voltages $V_1, V_2, V_3 \dots V_n$ appear successively as the input voltage increases and will vary according to FIG. 2.

A second group of Zener diodes $Z'_1, Z'_2 \dots Z'_n$ are connected in series with a second silicon diode D'_1 having a conduction direction opposite to that of D_1 so that,

2

when the polarity of the input voltage V_1 is inverted, output voltages $V'_1, V'_2 \dots V'_n$ appear successively at the junction points of the different Zener diodes $Z'_1, Z'_2 \dots Z'_n$. The variation of these voltages $V_1, V_2 \dots V_n$ and $V'_1, V'_2 \dots V'_n$ appearing at the corresponding output terminals when the input voltage increases is shown at FIG. 2.

The silicon diodes D_1 and D'_1 are necessary to prevent direct conduction by the Zener diodes.

It is evident that all these voltages are represented by straight lines having the same slope but spaced from one another. In order to make possible the variation of the slope of these voltages, they are applied each to a potentiometer as shown at FIG. 3. For example, the slope of the output voltage V_k can be changed by adjusting the potentiometer P_k connected to the junction point of two adjacent Zener diodes Z_k and Z_{k+1} . The sum of the voltages taken across the different potentiometers similar to P_k will constitute a resultant output voltage which varies according to a non-linear function of the input voltage, approached by a broken straight line, the slope of which continuously increases.

To produce an output voltage varying according to an arbitrary function of the input voltage, the circuit shown at FIG. 4 may be employed. It comprises two elements similar to that of FIG. 1, fed by equal voltages but having opposite polarities.

The first element is constituted by the Zener diodes $Z_{11}, Z_{21}, \dots Z_{n1}; Z'_{11}, Z'_{21}, \dots Z'_{n1}$ and the silicon diodes D_{11} and D'_{11} . Potentiometers $P_{01}, P_{11}, P_{21} \dots P_{n1}; P'_{11}, P'_{21} \dots P'_{n1}$ are connected between the ground and the common point of the silicon diodes D_{11} and D'_{11} and the respective common points of the different Zener diodes. Similarly, the second element comprises the Zener diodes $Z_{12}, Z_{22} \dots Z_{n2}; Z'_{12}, Z'_{22} \dots Z'_{n2}$, the silicon diodes D_{12}, D'_{12} and the potentiometers $P_{02}, P_{12}, P_{22} \dots P_{n2}; P'_{12}, P'_{22} \dots P'_{n2}$. The two elements are fed respectively by input voltages V_{1+} and V_{1-} which are equal but of opposite polarities. The voltages taken at the different potentiometers of the two elements are applied to a summation circuit S which supplies an output voltage V_0 equal to the sum of these voltages. It is obvious that, by suitably adjusting the different potentiometers, any desired shape can be obtained for the output voltage V_0 .

A particular embodiment shown at FIG. 5 allows replacement of the two series of Zener diodes of FIG. 4, by a single one, in cases where the output voltage is required to vary with the input voltage according to functions which are symmetrical with respect to the vertical axis. This layout, which results in an economy of half the Zener diodes, is particularly interesting for use in operations of the type:

$$xy = \frac{(x+y)^2 - (x-y)^2}{4}$$

FIG. 6 shows the application of the principle of smoothing the angles of the broken line representing the function. This principle has been disclosed by the inventor in a communication at the International Analogy Computation Meeting, September 1955. It consists of superimposing on the voltage at the junction point of two adjacent portions of the broken line a voltage, preferably of triangular shape as a function of time, having a frequency notably higher than the maximum frequency of the voltages applied to the operator. In the case of a triangular voltage, the smoothing has a parabolic shape.

In FIG. 6, high frequency signals supplied by suitable sources such as G_k, G'_m and each adjustable by means of potentiometers R_k, R'_m are applied through condensers C_k, C'_m to the potentiometers P_k, P'_m which are connected to the common points of the Zener diodes Z_k, Z_{k+1}, Z'_m ,

Z'_{m+1} through respective silicon diodes d_k, d'_m , the conduction direction of which corresponds to the direction of the current flowing from the input terminals through the Zener diodes into the slope-adjusting potentiometers.

Referring now to FIG. 7 which represents a complete schematic of a non-linear functional operator according to the invention, two series of Zener diodes and silicon diodes, designated by the same references as in FIG. 4, are fed with equal voltages, but having opposite polarities, respectively supplied by an input amplifier 1 and an inverting amplifier 2. This amplifier has a gain equal to 1 and it only inverts the polarity of the voltage supplied by the amplifier 1. The input voltage, at the terminals 3 is applied to the input of the amplifier 1 through a resistance 4.

The junction points of the Zener diodes are connected through silicon diodes $d_{11}, d_{21} \dots d_{n1}, d'_{11}, d'_{21} \dots d'_{n1}$ and $d_{12}, d_{22} \dots d_{n2}, d'_{12}, d'_{22} \dots d'_{n2}$ the groups of which have alternate polarities, to commutators, designated by the general references $K_1, K_2 \dots K_m$, having movable contacts $a_1, a_2 \dots a_m$ which can be operated manually or automatically. The commutators are connected together so that the voltage at any one of the junction points of the Zener diodes can be applied to any one of the leads $b_1, b_2 \dots b_m$ connected respectively to potentiometers $P_1, P_2 \dots P_m$, the voltages of which are applied, through resistances $r_1, r_2 \dots r_m$, to the input of an output amplifier 5. The potentiometers can also be operated manually or automatically. It can be readily understood that this amplifier receives the sum of m different voltages which can be chosen in any desired manner among the different junction points of the Zener diodes to reproduce the desired non-linear function. The signal is amplified by the amplifier 5 and appears at its terminals 6. The gain of the amplifier 5 can be adjusted by means of a switch 7 and resistances such as 8, 9, 10.

The smoothing of the angles of the generated function is achieved as described above by applying high frequency voltages to the leads $b_1, b_2 \dots b_m$ through condensers $C_1, C_2 \dots C_m$. These voltages are taken at potentiometers $R_1, R_2 \dots R_m$ fed by a suitable generator 11.

The generated function can be shifted horizontally by applying to the input terminal of the amplifier 1 a D.C. voltage which can be adjusted positively or negatively by means of a potentiometer 12 fed by a suitable D.C. source 13. In the same manner, the vertical shifting of the curve is achieved by applying to the input of the amplifier 5 a D.C. voltage, through a resistance 14, supplied by a source 15 and adjustable by means of a potentiometer 16.

Evidently the invention is not exclusively limited to the embodiments described and it is possible to bring about several modifications in the shape, layout and constitution

of some of the elements entering its realization without departing from the scope of the invention.

I claim:

1. A non-linear functional operator having input and output terminals, the output voltage of which is a non-linear function of the input voltage, said function being graphically representable by approximation by a broken line, comprising at least one branch constituted by a plurality of Zener diodes connected in series, all in the same direction, said branch being connected, at one end, to an input terminal, through a silicon diode poled to permit flow of current in the breakdown direction of the Zener diodes, a plurality of potentiometers connected between the ground and respectively the input terminal and each of the successive junction points of the Zener diodes, and a summation circuit to add the voltages taken at the different potentiometers the output voltage of said summation circuit being applied to the output terminal of the operator.
2. A non-linear functional operator, having an output terminal and two symmetrical input terminals, to which input voltages equal and of opposite polarities are to be applied, comprising two circuits each relative to one input terminal and formed by two branches each constituted by a plurality of Zener diodes connected in series, all in the same direction, each branch being connected, at one end, to the input terminal relative to the circuit, through a silicon diode poled to permit flow of current in the breakdown direction of the Zener diodes, the two branches having reverse directions of flow with respect to the common input terminal, a plurality of potentiometers connected between the ground and respectively the input terminals and the successive function points of the Zener diodes of both circuits, and a summation circuit to add the voltages taken at the different potentiometers, the output voltage of said summation circuit being applied to the output terminal of the operator.
